UNITED STATES PATENT OFFICE

2,419,967

FUSE

Louis J. Rhein, Aberdeen, Md.

Application July 5, 1943, Serial No. 493,527

1 Claim. (Cl. 102—81.6)

(Granted under the act of March 3, 1883, as amended April 30, 1928; 370 O. G. 757)

1

The invention described herein may be manufactured and used by or for the Government for governmental purposes without the payment to me of any royalty thereon.

The present invention relates to a fuse structure which is useful in firing an explosive charge and is particularly useful with hand grenades.

It is an object of the present invention to provide a fuse which may be easily manufactured without the use of complicated machining operations or the use of critical materials.

A further object resides in a fuse which is simple in construction and readily assembled.

A further object resides in the provision of a mechanism which prevents the reuse of a grenade or other projectile on which the fuse may be attached should the device fail to explode on contact.

To these and other ends, the invention consists in the construction, arrangement and combination of elements described hereinafter.

Fig. 1 is a fragmented elevational view of a grenade and attached fuse.

Fig. 2 is a longitudinal sectional view showing the parts in armed position.

Fig. 3 is a similar fragmentary view showing the parts in firing position.

Fig. 4 is a similar fragmentary view showing the parts in permanent dud position.

Figs. 5 and 6 are transverse sectional views on the lines 5—5 and 6—6 respectively.

Fig. 7 is a fragmentary elevational view of a modified fuse.

The fuse comprises a housing formed of two parts 1 and 2 with the lower portion 2 provided with a threaded extension 3 which is adapted to be attached to a grenade 4 or other explosive container.

The housing is formed with angular surface in such a manner as to form an "all ways" fuse. The angular surfaces of the housing 1 and 2 co-acts with the juxtaposed surfaces on the relatively movable fuse bodies 5 and 6. The angular surfaces are so disposed that when the fuse receives a sharp blow or jar, the fuse bodies 5 and 6 will tend to move toward one another regardless of the direction of the applied blow or jar. The fuse body 5 is urged into spaced relation to the fuse body 6 by means of a spring 7 and held in such a position by means of the locking balls 8. The locking balls are held in spaced relation and in contact with fuse body 6 by the spacers 9 and the arming pin 10. The spring 11 biases the arming pin 10 in an outward direction but is

held by the lever 12 and safety pin 13 attached to the ring 14.

The fuse 5 carries a firing pin 15 which is adapted to contact and function the primer 16 when there is relative movement of the fuse bodies 5 and 6. The primer 16 on being hit by the firing pin 15 discharges the igniter or detonator 17 as the case may be and therefore ignites or detonates the charge 18 in the grenade or other missile.

The fuse body 6 carries spring pressed dud lock plungers 19 which engage the annular depression 20 in the dud lock disk 20. On downward movement of the fuse body 5 relative to the fuse body 6 the dud lock disk is carried downward by the fuse body 5 into the position shown in Figure 3 and the dud lock disk remains in such position when the fuse bodies return to normal position. On the return of the fuse bodies to normal position, the dud lock plungers 19 are urged into a position to lock the fuse bodies in the normal position as shown in Figure 4 and prevent the re-use of the grenade or other structure to which the fuse may be attached.

25 The operation of the fuse is as follows: With the hand grasping the grenade and lever 12, the safety pin and ring 13, 14 is pulled free of the lug on the upper surface of the casing 1. Upon release from the hand the lever 12 and the arming pin 10 are thrown free by spring 11. The locking balls 8 and spacers 9 which hold the fuse in safety position are released by the arming pin 10 and move into the space vacated by the arming pin 10, as shown in Figure 2, thereby making the fuse bodies 5 and 6 susceptible to relative motion upon contact of the grenade with a solid object. Upon impact, the fuse bodies 5, 6 move relative to one another due to the "all ways" construction of the casing 1, 2 causing the firing pin 15 to function the primer 16 which ignites or detonates the grenade filler 18 through the intermediary of the igniter or detonator 17.

45 The relative movement of the fuse bodies 5 and 6 on impact causes the dud lock disk 20 to be disengaged from the dud locking plungers 18 and to be carried to the bottom of the recess in the fuse body 6 and to remain in such a position when the fuse body 5 is returned to normal position by the spring 11. The return of the fuse body 5 to 50 normal position permits the dud locking plungers to move into a position as shown in Figure 4 and to lock the fuse body 5 in the upper position. The dud locking plungers act as a safety to prevent the grenade or other device, to which the fuse 55 may be attached, from being exploded if picked

up by the enemy and thrown back against the troops which originally used the grenade, should the grenade fail to work as designed to work on the original impact.

The fuse has been shown as being provided with a spring 11 to eject the lever 12 and the arming pin 10 for purpose of clarity. The use of the spring 11 is optional and the fuse may be made and used without such a spring. If the spring is omitted the lever 12 and arming pin 10 will be thrown clear from the fuse due to the tumbling action of grenade when the same is thrown.

The fuse as shown in Figure 7 may utilize the spring 23 to eject the arming pin 21 through the action of radial tension of the spring 23. The spring 23 tends to compress the locking pins 22 against the angular surface of the arming pin 21 and exert an outward pressure which is sufficient to eject the same. The remainder of the fuse in Figure 7 is similar to that of Fig. 1.

I claim:

A fuse comprising a casing, two main body members in the casing movable to and from each other and carrying coacting firing components, resilient means holding said members normally distended, one of said members being provided with a bore extending laterally therethrough, an

expendable arming pin intersecting the bore, removable blocking means at the outer end of the bore, additional blocking means in said bore between the first mentioned blocking means and the expendable pin and holding said first mentioned blocking means in position, both of said blocking means being normally held in blocking position by said pin and released when said arming pin is expended to permit relative movement of said members.
